DESCRIPTION

Jun. 15, 2018 (CN) 2018 3 0308639

FIG. 1 is a front view of a thermal imager for temperature measurement of my new design;

(51) **LOC (12) Cl.** **16-05**

FIG. 2 is a left view of the thermal imager for temperature measurement shown in FIG. 1;

(52) **U.S. Cl.**

FIG. 3 is a right view of the thermal imager for temperature measurement shown in FIG. 1;

(USPC **D16/219**; D10/52

FIG. 4 is a top view of the thermal imager for temperature measurement shown in FIG. 1;

(58) **Field of Classification Search**

FIG. 5 is a bottom view of the thermal imager for temperature measurement shown in FIG. 1;

USPC D10/52; D16/219

FIG. 6 is a back view of the thermal imager for temperature measurement shown in FIG. 1; and,

CPC .. G01J 5/026; G01J 5/0265; G01J 2005/0077;

FIG. 7 is a perspective view of the thermal imager for temperature measurement shown in FIG. 1.
